JOHN C. REED, OF STEELTON, PENNSYLVANIA, ASSIGNOR TO BETHLEHEM STEEL COMPANY

PNEUMATIC CONVEYER SYSTEM

Application filed September 14, 1927. Serial No. 219,380.

My invention relates to improvements in pneumatic conveyer systems and more generally to the type where two separate stations are connected by a single tube.

5 The object of my invention is to provide an electrically controlled conveyer system which contains means for signalling the receiving station and for automatically admitting compressed air to the conveyer tube 10 when it is desired to send an article or message, contained in a carrier, therethrough.

Another object of my invention is to provide means for automatically rendering the signalling means inoperative and for automatically and simultaneously shutting off the air supply as soon as the carrier is discharged from the tube, thus returning the conveyer system to its normally inert position.

The novel features of my invention will 20 be more fully understood from the following description and claims taken with the accompanying drawings in which:

Two stations, designated A and B, respectively, are connected by a pneumatic conveyer system having a single tube 10 through which carriers 11 are pneumatically passed.

The tube 10 is provided at its end with deflectors 12 and 12', which serve to retard the velocity of the carriers and directs them 30 downwardly upon their discharge from the tube. Connected to conveyer tube adjacent the ends at stations A and B are air supply pipes, designated as 13 and 13', respectively. These pipes are connected to a main compressed air supply pipe 14 through the branch lines 15 and 15', respectively. In each of the latter I provide solenoid operated valves 16 and 16'. Openings 17 and 17' are provided 35 in the tube through which carriers 11 are inserted and are ejected, depending upon the direction in which the carriers are being conveyed. Covers 18 and 18' are provided for closing the openings 17 and 17', respectively, as hereinafter described. 19 and 19' are receiving platforms for the carriers and are provided with cushions 20 and 20', respectively, to deaden the impact when carriers are discharged from the system.

Referring now to the electrical circuit, 21 50 and 22 designate the 230-volt D. C. main

power line. 23 and 23' are double pole fused knife switches for connecting the electrical system to the main power line. 24 and 24' are solenoid operated switches having top and bottom contacts 25, 26, 27, 28 and 29, and 55 25', 26', 27', 28', and 29', respectively. The solenoids for operating these switches are designated as 30 and 30', and as their construction and operation are identical the description of only one of them will be given. 60 Solenoid 30 consists of a coil 31 and a movable core or armature 32 which is provided on one end with a contactor 33 and on the other with a contactor 34. Normally the core 32 is constrained to its outward position by 65 means of the coil spring 35 and in this position contactor 33 connects contacts 25 and 26. When the solenoid is energized the core is drawn inwardly, overcoming the pressure of the spring 35 and causing the contactor 33 70 to disconnect contacts 25 and 26 and to connect contacts 27 and 28, and also causing contactors 34 to make connections with contacts 29. Contactor 34 is connected to wire 55 which passes through the center of the core 75 32 and is insulated therefrom.

36 and 36' are solenoids for operating the air supply valves 16 and 16', respectively. As these solenoids are identical in construction and operation only one will be described. 80 Solenoid 36 consists of a coil 37 and a core 38 which forms the stem of the valve 16. The core 38 is held in its outward position by the coil spring 39 and in this position closes the valve 16. When the solenoid 36 is energized 85 the core 38 is drawn inwardly overcoming the pressure of the spring 39 and thus opening the valve 16.

40 and 40' are normally closed trip switches, the handles of which extend in the path of 90 the ejected carriers intermediate the deflectors 12 and 12' and the cushions 20 and 20' of the receiving tables 19 and 19'.

41 and 41' are 125-volt incandescent lamps 95 provided for signalling means.

42 and 42' are push buttons for initially rendering the system effective.

In operation, assuming that it is desired to send a message or article from station A to station B, through the conveyer tube 10 100

by means of the carrier 11, the switches 23 and 23' being closed and the covers 18 and 18' open, the sender places the carrier in the opening 17, closes the cover 18, and then 5 presses the button 42.

The operation of pressing the button 42 connects the contacts 43 and 44 and causes the current to flow from the main power line 21 through switch 23, wires 45, 46, solenoid coil 31, wire 47, push button 42 and wires 48 and 49. The current from wire 49 divides in wire 50, part of the current flowing through lamp 41, wire 51, switch 40, wire 52, contacts 25 and 26, wires 53, 54 and switch 23 to main line wire 22; and the other part of the current flowing through lamp 41', wire 51', switch 40', wire 52', contacts 25' and 26', wires 53', 54' and switch 23' to main line wire 22. The lamps 41 and 41' now being in 10 parallel with each other and in series with the coil 31 of solenoid switch 24, there will not be sufficient current passing through the lamps to cause either of them to be illuminated.

25 The current passing through the coil 31 of solenoid 30 will energize same and cause contactor 33 to break the connection between contacts 25 and 26 and the opening of this circuit will interrupt the current flowing 30 through lamp 41 and cause all of the current passing through the coil 31 to pass through the lamp 41' and will illuminate the same. The action of the solenoid will also close contacts 27 and 28 which are in parallel with 35 contacts 43 and 44 of the push button 42, making it unnecessary for the operator to longer push the button 42. The action of the solenoid will also close contactor 34 and contact 29 which will cause current to flow from 40 the wire 45 through contact 29, contactor 34, wire 55, coil 37 of solenoid 36, wire 54 and switch 23' to the minus side of the main power line. The current passing through coil 37 of solenoid 36 energizes same and 45 causes it to actuate the air valve 16. The opening of valve 16 allows air under pressure to be admitted, through the medium of the pipe 13, to the tube 10 at the rear of the carrier 11.

50 The air pressure will cause the carrier 11 to be conveyed through the tube 10 to station B where it is ejected and falls upon the cushion 20', which is supported by the receiving platform 19'. Just before the carrier reaches 55 the cushion 20' it strikes the handle of the switch 40' and causes it to trip. The tripping of the switch 40' breaks the electrical circuit and causes the solenoids 30 and 36 to become de-energized, thus causing the valve 60 16 to be returned to its normally closed position to prevent the admission of compressed air to the tube 10, and simultaneously extinguishes the lamp 41'.

As soon as the carrier passes the trip 65 switch the switch automatically returns to

its normally closed position and the conveyer system is again in condition for the transmission of a carrier from either station.

Similar operations take place when a carrier is sent from station B to station A.

From the foregoing it will be seen that I have devised a conveyer system which is controlled by a single operation of the sender of a carrier.

While I have shown my invention in but 75 one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described my invention what 85 I claim as new and desire to secure by Letters Patent is:

1. In a pneumatic conveyer system, a single tube connecting two stations, said tube having an opening at each end for the passage of an article, a closure member for said opening, a compressed air supply pipe connected adjacent each end of said tube, normally closed valves in said air pipes, an electrical circuit, signalling means, means for 90 rendering said electrical circuit effective, solenoid controlling means for said signalling means and said valves, said controlling means adapted to maintain said signalling means effective continuously during the presence of a carrier in the tube and a trip switch adapted to be actuated by the discharge of the article being conveyed for rendering the signalling means ineffective.

2. A pneumatic system for conveying 105 articles, comprising a pair of distant stations, a conveyer tube interconnecting said stations, said tube having an opening at each end thereof for the passage of an article to be transmitted from one station to the other, a closure for each of said openings, a compressed fluid pipe connected to said tube, a valve normally closing said pipe, a signalling device, an electrical circuit for operating said valve and said device, means for rendering said circuit effective, means for maintaining the signalling device effective continuously during the presence of a carrier in the tube, and means adapted to be actuated by the discharge of the article being conveyed for rendering the circuit ineffective.

3. A pneumatic system for conveying 115 articles comprising a pair of distant stations said tube having an opening at each end thereof for the passage of an article to be transmitted from one station to the other, a closure for each of said openings, a compressed fluid pipe connected to said tube, a valve normally closing said pipe, a signalling 125

device adapted to be illuminated, an electrical circuit for operating said valve and said device, means for rendering said circuit effective, means for maintaining said signalling device effective continuously during the presence of an article in the tube and means adapted to be actuated by the discharge of the article being conveyed for rendering said circuit and said signalling device ineffective.

In testimony whereof I hereunto affix my signature.

JOHN C. REED.
